INVENTOR:
MILTON TIBBETTS
BY *A. Ernestel*,
ATTORNEY.

UNITED STATES PATENT OFFICE

MILTON TIBBETTS, OF DETROIT, MICHIGAN, ASSIGNOR TO PACKARD MOTOR CAR COMPANY, OF DETROIT, MICHIGAN, A CORPORATION OF MICHIGAN

PISTON

Application filed June 12, 1928. Serial No. 115,427.

My invention relates to devices for compensating for dimensional changes in mechanical elements and due to expansion or contraction resulting from temperature variation, to which such an element may be subjected.

The general object of the invention is to control or modify such changes so as to maintain certain of the dimensions of the element substantially in a state of constancy or maintain a predetermined relationship between such an element and a cooperating element.

A particular object is to provide a piston for an internal combustion engine whose diameter will remain substantially constant under the conditions of varying temperature to which it is subjected when in operation, so that it will not be loose and noisy when cool or bind and score when hot.

One method, heretofore, of attempting to overcome this piston difficulty has been by providing a split skirt for the piston so that it would automatically spring inwardly when subjected to increased temperature, and when pressed by the cylinder walls, and automatically spring outwardly when subjected to decreased temperature and released by said cylinder wall, under the theory that a substantially constant diameter of the piston would thus be maintained and a proper fit secured under all variations of temperature to which the piston would be subjected.

However, in some cases it has been found that pistons constructed as just described, and particularly when made of aluminum, contract and change their diameter to such an extent as to become, when cold, loose and hence noisy. It will be apparent, also, that the degree of frictional resistance between the piston and cylinder will vary materially by changes in the temperature, and especially in the case of an aluminum piston and iron cylinder, even though it might not be noisily loose when cold.

In carrying out the principles of my invention, I provide the mechanical element with a thermally operated device which when subjected to variations of temperature produces a force resulting in motion which is transmitted to the element and caused to oppose the force which would produce movement in

the element, and if unopposed would result in a dimensional change in said element, and which latter force itself results from a similar variation of temperature.

In applying such principle to a piston, I provide the skirt of the latter with a longitudinal slot so that such skirt is normally capable of circumferential dimensional expansion or contraction independently of temperature variation. To the skirt I connect a thermally actuated device and in such a manner that a variation of temperature will effect a movement in the device, which is transmitted to the skirt wall and in a direction such as will decrease the diameter of the skirt in case it expands or maintain the diameter in case it tends to expand and increase the diameter in case it contracts or maintain its diameter in case it tends to contract.

The said invention therefore consists of means hereinafter fully described and particularly pointed out in the claims.

The annexed drawing and the following description set forth in detail certain means for carrying out my invention, the disclosed means, however, constituting but two of the various mechanical forms in which the principle of my invention may be employed.

In said annexed drawing:

Figure 1 represents an axial section of a piston embodying my invention.

Fig. 2 represents a transverse section taken upon the plane indicated by line II-II, Fig. 1.

Fig. 3 represents a section similar to that of Fig. 2, but showing a modified form of the invention.

In the illustrated embodiment of my invention, the piston 1 is provided with a head 2 and a skirt 3 integral with or joined to the head, the skirt and head being separated at the wall portions thereof by a circumferential slot 4 extending completely around the periphery of the piston 1, as shown in Figure 1. The skirt wall is intersected by a slot 5 extending longitudinally from top to bottom of same, and is shown in the drawing to be inclined with reference to the piston's axis.

As thus far described, the piston is of a construction heretofore known and does not constitute any part of my invention.

It will be observed, however, that the piston so constructed permits the skirt normally to be subjected to a dimensional change independently of temperature variation and 5 also is subject to such change as a result of such variation. By this I mean, for example, that an exterior mechanical compressive force may be applied to the dismounted skirt to reduce its diameter and thereby contract the 10 slot 5, or an expansive force applied to increase such diameter and enlarge the slot. Also that when subjected to increased temperature its diameter will be increased and the circumferential extent of the metal also 15 increased, while the slot is also somewhat enlarged.

The above construction is, however, in the form of my invention shown in Figs. 1 and 2, modified by providing additional metal upon 20 the interior of the wall of the skirt in the form of bead-like additions 6—6, respectively immediately adjacent the slot 5, and in these beads are respectively embedded and fixedly secured, as for example by casting, the ends 25 of a thermally-actuated loop-formed device 7 consisting of two flat superposed pieces of metal having different co-efficients of expansion as for example steel and brass, that plate having the greater coefficient of expansion 30 being located upon the outside of the loop. As is well known, such a combination of metals when subjected to varying temperature warps and produces or tends to produce motion in the device. In this case an increase 35 of temperature will cause the ends of the loop to approach or tend to approach and a decrease would cause same to recede or tend to recede from each other, and in either case may be used to transmit force to the wall of 40 the skirt adjacent to the slot. The force thus applied by the loop device 7 acts circumferentially of the skirt 3 and provides a circumferential dimensional change therein which is uniformly distributed about the circumference 45 of the skirt.

Such proportions and dimensions of the loop and its constituent parts and character of the metals are selected as will be necessary to produce a movement of the loop ends, sufficient 50 in its transmission to the skirt wall to counteract and equalize any expansive or contractive force developed interiorly of the skirt metal and due to the variation of temperature to which the piston is subjected in 55 the operation of the engine, and the external diameter of the skirt will hence remain substantially constant for all temperatures, as it will be understood that the amount of movement produced by the loop will vary 60 substantially directly as the temperature.

Should it be found that it is also desirable to allow for the expansion of the cylinder wall, the loop may be designed so that the force exerted upon the skirt would be sufficiently 65 less than an absolutely equalizing

force required to maintain a predetermined amount of clearance. In such case it would hence be seen that the expansive or contractive force in the skirt would be controlled rather than completely equalized. In this way allowance may be made for cylinder expansion and a constant relationship secured between the friction surfaces of the piston and cylinder so as to effect a constant frictional relation thereof for all the temperatures. 70 75

The proper design of the loop and proportioning of its parts may be determined empirically for any given engine, set of operating conditions, or character of piston, as will be apparent to those skilled in the art. 80

It will also be apparent to those skilled in the art that various forms of thermally operated devices may be used to accomplish the above-described object, and I have illustrated one such modification in Fig. 3. 85

In this latter instance, the device is generally flat with a centrally located bow 8, its ends being fixedly secured in ribs 9—9 respectively and preferably near the skirt wall as shown, so as to take advantage of all the leverage possible. In this latter form the metal having the greater coefficient of expansion would be located inwardly, that is on the side of the device adjacent the piston wall. 90 95

What I claim is:

1. The combination with a mechanical element normally capable of circumferentially uniform dimensional changes independently of temperature variation; of a thermally 100 actuated device connected with said element and adapted to apply force thereto circumferentially opposed to that force tending to effect circumferential dimensional change in said element and due to temperature variation; whereby such last-mentioned change may be controlled. 105

2. The combination with a hollow cylindrical mechanical element normally capable of circumferentially uniform dimensional changes independently of temperature variation; of a thermally actuated device connected with said element and adapted to apply force thereto circumferentially opposed to that force tending to effect circumferential dimensional change in said element and due to temperature variation; said device being arranged so as to maintain a substantially constant circumferential dimension on the part of said element. 110 115

3. A piston capable of circumferentially uniform dimensional changes independently of temperature variation; and provided with a thermally actuated device connected therewith and adapted to apply force thereto acting circumferentially and in a direction opposite that tending to effect a circumferential dimensional change in said piston due to temperature variation. 120

4. A piston having its wall formed with a 125

longitudinally extending slot and provided with a thermally actuated device connected with the piston wall on opposite sides of said slot, said device adapted to apply force to said opposite sides varying as its temperature.

5. A hollow piston having a head, and a skirt formed with a longitudinal slot, the wall of said skirt being separated from said head throughout the periphery of the piston, said skirt being provided with a thermally actuated device connected with the wall portion adjacent said slot and adapted under the influence of an increased temperature to apply a force to said wall portion tending to contract said slot.

10. 6. A piston having a head, and a skirt formed with a longitudinal slot, the wall of said skirt being separated from said head; and a thermally actuated device connected with said skirt and adapted, when subjected to an increased temperature, to exert on said skirt a force acting uniformly circumferentially and opposed to that force set up there-

15. 25 in by such increased temperature.

7. A piston having a head, and a skirt formed with a longitudinal slot, the wall of said skirt being separated from said head; and a thermally actuated device connected with said skirt upon opposite sides of said slot and adapted, when subjected to an increased temperature, to exert on said skirt a force opposed to that force set up therein by such increased temperature.

30. 35. 8. A hollow piston having its wall formed with a slot and provided with a device comprised of two metals of different coefficients of expansion and connected with said wall upon opposite sides of said slot and adapted

40. 45. 9. A hollow piston having its wall formed with a slot and provided with a device comprised of two superposed metal plates of different coefficients of expansion and connected with said wall upon opposite sides of said slot and adapted upon thermal expansion to contract said slot.

10. 50. A hollow piston having its wall formed with opposed beads and a slot therebetween, and a device comprised of two superposed metal plates of different coefficients of expansion and connected at its ends respectively to the outer walls of said beads, the outer metal plate having the greater coefficient of expansion.

55. 11. A piston having a head, and a skirt formed with a longitudinal slot extending from its top to its bottom, the wall of said skirt being separated from said head; and a thermally actuated device connected with said skirt and adapted, when subjected to an increased temperature, to exert on said skirt a force entirely opposed to that force set up therein by such increased temperature.

60. 65. 12. A piston having a head, and a skirt

formed with a longitudinal slot, the wall of said skirt being separated from said head; and a thermally actuated device connected with said skirt upon opposite sides of said slot and adapted, when subjected to temperature variations, to exert on said skirt a force opposed to that force set up therein by such temperature variations.

Signed by me this 11th day of June, 1926.
